UNITED STATES PATENT OFFICE

169,391

BICYCLE STABILIZER ATTACHMENT

Harold H. Ring, Rockford, Ill., assignor to Monark
Silver King, Inc., Chicago, Ill., a corporation
of Delaware

Application November 28, 1952, Serial No. 22,470

Term of patent 14 years

(Cl. D90—8)

To all whom it may concern:

Be it known that I, Harold H. Ring, a citizen of the United States, residing at Rockford, in the county of Winnebago and State of Illinois, have invented a new, original, and ornamental Design for a Bicycle Stabilizer Attachment, of which the following is a specification, reference being had to the accompanying drawings, forming part thereof.

In the drawings:

Fig. 1 is a side elevational view of a bicycle stabilizer attachment showing my new design;

Fig. 2 is a top plan view, and

Fig. 3 is a perspective view.

The dominant features of the invention are shown in full lines.

I claim:

The ornamental design for a bicycle stabilizer attachment, as shown and described.

HAROLD H. RING.
